UNITED STATES PATENT OFFICE.

GEORGE J. HUNTLEY, OF BALTIMORE, MARYLAND, ASSIGNOR TO THE CROWN CORK & SEAL COMPANY OF BALTIMORE CITY, OF BALTIMORE, MARYLAND, A CORPORATION OF MARYLAND.

FILLING-HEAD.

1,371,244.

Specification of Letters Patent. Patented Mar. 15, 1921.

Application filed July 20, 1917. Serial No. 181,678.

To all whom it may concern:

Be it known that I, GEORGE J. HUNTLEY, a citizen of the United States, residing at Baltimore city, and State of Maryland, have 5 invented certain new and useful Improvements in Filling-Heads, fully described and represented in the following specification and the accompanying drawings, forming a part of the same.

10 This invention relates to improvements in filling heads for liquid packaging machines.

In bottle filling machines of the type in which the filling head reciprocates to and from the bottle, the part making contact with 15 the bottle is ordinarily of some resilient material, so as to avoid breaking the bottle and to provide at the same time an effective seal between the bottle and the filling head. Furthermore, in such devices, it is consid-

20 ered desirable, in order to avoid the dripping of the liquid being packaged, and for other reasons, to have a valve such that the liquid admission passage and the air exit passage are completely closed by the valve 25 when the head is raised away from the bottle. It has been found, however, that when the pressure of the head on the resilient sealing member is removed on the upstroke of the head, the return of this resilient seal-

30 ing member to its normal uncompressed condition causes in the bottle a suction of such strength that often times a bottle will be raised up by the movement of the head unless prevented by brakes or similar mecha-

35 nism.

It is one of the objects of this invention to provide a filling head that eliminates this raising of bottles and at the same time to attain this end by means of a simple, inexpensive construction which avoids the use 40 of brakes acting on the bottles and other similar devices.

In a filling head of the type mentioned, namely, one in which a seal is effected between the head and the receptacle, provision 45 is ordinarily made for the escape of air expelled by the inflowing liquid, by an air exit passage which communicates with a port or ports in a member entering the receptacle, as, for example, the valve itself. As soon, therefore, as the level of liquid in 50 the receptacle rises high enough to cut off such air-exit port, the flow of liquid will cease. Since this cutting off of the air-exit 55 port occurs sooner or later according to the

position of the valve or other port carrying member with respect to the receptacle, it follows that the level of liquid depends upon the extent to which the valve or other member penetrates into the receptacle. 60

It is a further object of the present invention to provide means for fixing the position of the air-exit port or ports with respect to the receptacle being filled, by fixing the extent of penetration into the receptacle of 65 the valve or other port carrying member, thereby determining the liquid level.

The following specification describes and the accompanying drawing illustrates preferred embodiments of this invention, it being understood that changes may be made in the form, construction and arrangement of the parts without departing from the invention. 70

In the drawing—

75 Figure 1 is a vertical cross sectional view of a filling head constructed in accordance with this invention, showing the head removed from the receptacle to be filled, with the valve closed.

Fig. 2 is a similar view, the section being taken at right angles to the section of Fig. 1, showing the head in filling position with valve open.

Fig. 3 is a similar view taken on the same 85 section as Fig. 2, showing the parts at the start of the up-stroke of the head.

Fig. 4 is a cross-sectional view taken on the line 4—4 of Fig. 2.

Fig. 5 is a detail view showing in plan a 90 portion of the sealing gasket.

Fig. 6 is a side elevation of the same, and

Fig. 7 is a view (reduced) in side elevation (with parts in section) showing a modification of the apparatus shown in Figs. 1 95 and 2.

A filling head constructed in accordance with this invention includes a passage for directing the liquid to be packaged from a reservoir to the bottle or other receptacle; 100 means for permitting the escape of the air expelled during filling; a valve for cutting off the liquid and air passages while the head is still in contact with the bottle; and means for bringing head and bottle together and separating the same. While the construction and arrangement of these features may vary, in the embodiment of the invention shown, the liquid passes out from the reservoir 8 through a valve tube 9 110

slidably mounted in a stuffing box 10 attached to the bottom of the reservoir. This valve tube extends well into the reservoir and has near its upper end ports 11 for admitting the liquid contained in the reservoir. Telescoping within the valve tube at its lower end, and communicating therewith, is a tubular valve cage 12, the lower and valve embracing portion of which is 10 slightly constricted and terminates in an outwardly flaring flange 13 which serves as a seat for a valve 14. This valve has, at its bottle-entering end, an imperforate conical head 15, the base of which is slightly greater 15 in diameter than the adjoining portion and the shoulder 16 thereby formed slopes downwardly to form a seating surface corresponding to the valve seat above mentioned. The valve at the upper end has a cylindrical 20 stem 17 which is threaded on its interior to engage the threaded end of an air exit tube 18 which passes up through the valve tube 9 to a point above the liquid in the reservoir and which operates the valve as hereinafter 25 appears. The internal passage 19 formed by the cylindrical stem of the valve and which communicates with the air-exit tube extends down almost to the imperforate head where it communicates with two diametrically 30 opposed air-exit ports 20 formed in the side of the valve. For passage of the liquid into the bottle, when the valve is opened, the side of the valve, at points substantially 90° removed from the air-exit 35 ports, is formed with two recesses 21 terminating at a point above the valve head and open at the top. It will be seen that, due to the construction described, when the valve head is moved away from its seat, 40 liquid flowing through the tube and cage enters the bottle 100 by way of the passages 21 formed between the valve and cage, while the expelled air goes out by way of the ports 20 up through the interior passage 19 of the 45 valve stem to the air-exit tube 18. When, however, the valve is seated, both liquid-admission passages and air-exit ports are cut off and the valve cage is completely closed at the bottle end.

50 The filling head is lowered and raised by means of a lever 22 oscillated by any suitable mechanism. This lever is pivoted to a yoke 23 which is connected by two links 24 with two pins 25 formed on a ring 26 which 55 is fixedly mounted on the valve tube 9 so that the latter is reciprocated by the oscillation of the lever. The valve-carrying, air-exit tube is connected with the valve tube, as shown at 27, so that valve tube, air tube and 60 valve all have the same movement. Movement of the valve cage is effected as follows: Backed by the ring 26 is a coil-spring 28, the other end of which seats on a flange-like shoulder 29 formed on the valve cage. 65 This spring is under slight initial compres-

sion. The cage is held up by the valve, but when the valve moves downward, the cage is free to follow, and does, in fact, move down with the valve under the influence of the spring, gravity, and the friction of its 70 contact with the moving tube, until stopped, as hereinafter described. When, however, the valve moves upward, its contact with the bottom of the cage causes the latter to move upward also. Although the cage 75 stops, as just mentioned, at a certain point in the down stroke of the head, the valve to be opened, must continue downward away from its seat. Means is provided for giving the valve a fixed stroke with respect to 80 the valve cage. In the embodiment of the invention shown this is accomplished as follows: After the valve cage stops, the valve tube, which governs the movement of the valve, continues downward, telescoping 85 over the now stationary cage until the bottom of the tube strikes the shoulder 29 on the cage and this acts as a stop to limit the movement of valve tube and valve, and so the valve is given a fixed movement after 90 the cage stops.

The invention includes means for effecting a seal between the filling head and the bottle during the filling operation, and for venting the bottle after filling, on the up-stroke of the head, but while the head is still in contact with the bottle, thereby to prevent the bottle from being raised and without the use of mechanical brakes and the like. In the best constructions embodying the invention, this will comprise a resilient member making contact under pressure with the rim of the bottle, so as to make a tight seal during filling, but at the same time having provision for venting the bottle 95 upon withdrawal of the head and before the head is moved sufficiently to cause the bottle to be raised. For example, this may be a rubber gasket having a passage providing communication between the bottle and the 100 outside atmosphere, which passage is closed by compression of the gasket during filling, and opened, upon removal of the pressure, by inherent resiliency of the gasket. While the construction of such sealing and venting 105 means may be varied, in the construction illustrated, it consists of a two-part resilient gasket 30 carried by the lower end of the valve cage and consisting of two rubber rings. The upper ring 31 is made to fit the 110 valve cage snugly and is provided on its lower face with a plurality of equally spaced radial ribs 32, and on its upper face with corresponding grooves 33. The lower ring 34, which makes contact with the bottle, has flat faces and the diameter of its central opening is somewhat larger than the diameter of the valve cage, so that there is provided an air passage 35 between ring and cage. This loose fitting portion of the gas- 115 120 125 130

ket is prevented from falling off by the flaring flange 13 of the valve cage.

The gasket 30 carries a valve cage guard which consists of a flat annular member 36 which rests on the top of the upper ring 31 and has a depending cylindrical skirt 37 surrounding the gasket, but leaving a space between the two, and extending down far enough to surround the top of the bottle neck during filling, as shown in Fig. 2.

When the gasket is in its normal uncompressed state there is an air passage up between the valve cage and lower ring 34 and out between the two rings, via passages 38 between the ribs 32, to the atmosphere. When, however, the lowering of the head compresses the gasket (as hereinafter described) these ribs 32 are flattened out, thus closing or eliminating the air passages 38, so that the gasket effects a seal between the bottle and the valve cage.

As before stated, the invention includes means for fixing the extent of penetration into the bottle, of the member carrying the air-exit ports, this member being the valve in the present embodiment. In constructions embodying the invention most advantageously, this is accomplished by giving the valve a fixed stroke with respect to the valve cage and fixing the position, on the cage, of the sealing gasket, the contact of which with the bottle stops the cage. This may be done in various ways, as, for example, by providing for the gasket a stop the position of which may be fixed with respect to the cage. While this may be accomplished by a variety of constructions, the drawing illustrates two exemplifications.

Referring to Figs. 1 to 4 inclusive, the valve stem, just below the shoulder 29, is screw-threaded to receive a correspondingly threaded adjusting nut 39 which has a downwardly extending cylindrical stop-portion 40, the bottom of which engages the valve cage guard 37 carried by the gasket. When the gasket engages the bottle rim and is forced against the stop member 40, the valve cage can descend no farther. Since the valve has a fixed stroke after the cage stops, the extent of the valve penetration into the bottle depends on the point where the cage stops and this, in turn, depends on the given position of the gasket, governed by the stop. To change the extent of penetration of the gasket and illustrated in connection with a bottle, down on the cage, so that the gasket will be stopped in a different position with respect to the cage. For example, if the adjusting nut is moved upward on the cage from the position illustrated, and the gasket is pushed up to it (or allowed to be pushed up by contact with the first bottle filled) the cage will make a greater descent before the gasket stops it and consequently the valve will make a greater penetration. Thus the

valve's penetration is fixed by adjustment of the stop-forming member 40.

The invention includes means for covering substantially the entire head and at the same time providing means for manipulating the adjusting nut. While this may be attained by numerous constructions, in the embodiment illustrated, a cover or guard is provided in the form of a large cylindrical inclosure 41 surrounding the filling head. To secure this cover in place and at the same time to have it rotatable, it is provided at the top with an inturned flange 42 which is held between the ring 26 and the spring 28. The cover is of such length as to overlap the valve cage guard 37 so that the head is substantially inclosed by these two members. To operate the adjusting nut the cover 41 is provided with a plurality of integrally stamped key-ways 43 which fit over ribs 44 formed in the side of the adjusting nut, so that rotation of the cover 41 turns the nut to fix the position of stop portion thereof with respect to the cage.

To lock the cover in non-rotatable position, it is provided with one or more radial ribs 45 formed on the top flange 42 which fit corresponding grooves in the bottom of the ring 26. When the head is in filling position, the spring 28 is under such compression that the operating cover 41 is pressed firmly up against the ring 26 and the engagement of the ribs with the grooves prevents any alteration in the adjustment of the nut 39 during a given filling operation.

Referring to the second construction illustrated, that shown in Fig. 7, just below the cage shoulder 29, there is fixedly mounted on the valve cage, an annular member 46 having a downward extending, cylindrical skirt 47, the bottom of which engages the gasket carried guard 37 and forms a stop, as the bottom of the member 40 does in the construction just described. This skirt may be of any desired length and by fixing its length the position of the gasket is determined and thus the extent of valve penetration is fixed. When it is desired to provide a greater or less valve penetration a stop-forming skirt of less or greater length is substituted.

To recapitulate, the operation of the device, Fig. 1 shows the neck of a bottle 100 which has been placed in proper position by any suitable means beneath the head and in alignment with the valve cage. Assuming that the lever 22 is suitably oscillated, the valve tube, air-exit tube and valve descend together, the valve cage accompanying them, as before described, until the gasket engages the bottle rim. At this point the valve cage has entered the bottle but the valve is still closed. As the cage-carried, stop forming member 40 (or 47) engages the gasket-carried guard 37, the cage stops. The valve

tube and valve, however, continue downward until the bottom of the tube is stopped by the shoulder 29, thus giving the valve its fixed stroke relative to the cage, and this 5 movement of the valve displaces it from its seat to open the liquid admission passages 13 and air exit ports 20. The movement of the tube subsequent to the stopping of the cage compresses the spring 28 against the 10 cage shoulder 29, which causes the gasket to be tightly pressed against the bottle rim, thus flattening out the ribs 32 on the upper ring. Consequently a seal is effected between 15 valve cage and bottle at the time the valve is open. At this point the parts are in the position shown in Fig. 2.

As soon as the liquid flowing into the bottle rises high enough to cut off the air-exit ports 20 in the valve the flow ceases. 20 The movement of the operating lever now makes its stroke to raise the head. As the tube moves upward it releases the spring compression, the valve at the same time making its closing stroke. As soon as the 25 valve engages its seat and starts to lift the valve cage, the gasket is released from pressure and its inherent resiliency causes it to return to normal condition, thus opening the passages between the ribs and forming 30 an air vent for the bottle while the lower ring is still in contact therewith, as shown in Fig. 3. Further movement of the valve lifts the valve cage away from the bottle and the parts are again in the position shown 35 in Fig. 1 ready to descend for the next bottle.

Should it be desired to change the liquid level at any time, the penetration of the valve is fixed by adjusting the position of the 40 nut 39 or substituting a different stop forming skirt 47, as before described.

Although the invention has been described and illustrated in connection with a bottle, it is to be understood that it is not restricted 45 to use with any particular kind of receptacle.

What is claimed is:—

1. In a filling head movable with respect to the receptacle to be filled, a valve cage, 50 a valve for closing the same, a two-part gasket comprising a resilient ring carried by the valve cage and tightly fitting the same, and a receptacle engaging resilient ring loosely embracing said valve cage, 55 means for separating said rings in their normal condition to provide an air passage therebetween, said rings being compressed against the receptacle upon movement of the head into filling position thereby to close 60 said passage and effect a seal between the receptacle and the valve cage.

2. In a filling head movable with respect to the receptacle to be filled, a valve cage, a valve for closing the same, a two-part 65 gasket comprising a resilient ring carried

by the valve cage and tightly fitting the same, and a receptacle engaging ring loosely embracing the valve cage, one of the opposing faces of said rings being substantially flat and the other irregular in its normal un- 70 compressed condition.

3. In a filling head, a valve cage, a valve for closing the same, a two part resilient gasket, carried by the cage and having associated therewith an air venting passage and 75 comprising a lower ring loose on the cage and an upper ring having a sealing fit on the cage, and means for causing said passage to be closed when the filling head and the receptacle are in filling relation. 80

4. In a filling head movable with respect to the receptacle to be filled, a valve cage, a valve for closing the same, a two part resilient gasket carried by the valve cage, one of which parts engages the receptacle, 85 means for separating the parts of said gasket in their normal condition to provide an air passage therebetween, said gasket being compressed against the receptacle upon movement of the head into filling position 90 thereby to close said passage and effect a seal between the receptacle and the valve cage.

5. In a filling head movable with respect to the receptacle to be filled, a valve cage, a valve for closing the same, a two part 95 gasket comprising resilient rings carried by the valve cage, one of the opposing faces of said rings being substantially flat and the other irregular in its normal uncompressed condition. 100

6. In a filling head movable with respect to the receptacle to be filled, a valve cage, a valve for closing the same, a two part gasket comprising a pair of resilient rings carried by the valve cage, the receptacle 105 engaging ring having associated therewith a passage between itself and the valve cage, means for separating the two rings in their normal condition to provide an air passage therebetween, said rings being compressed 110 against the receptacle upon movement of the head into filling position thereby to close said air passage and effect a seal between the receptacle and the valve cage.

7. In a filling head movable with respect 115 to the receptacle to be filled, a valve cage, a valve for closing the same, a two part gasket comprising two resilient rings carried by the valve cage, the receptacle engaging ring having associated therewith a passage 120 between itself and the valve cage, one of the opposing faces of said rings being substantially flat and the other irregular in its normal uncompressed condition.

8. In a filling head, a valve cage relatively 125 movable with respect to the receptacle to be filled and inclosing a liquid admission and an air-exit passage, a valve having therein a port communicating with said air-exit passage, means whereby said valve moves a 130

- fixed distance with respect to said cage on its opening stroke, a gasket for contacting with the receptacle to effect a seal between the cage and the receptacle and movable 5 with respect to said cage, a stop connected with said cage for limiting the relative movement of the gasket, thereby to stop the cage upon contact of the gasket with the receptacle, and means for fixing the position of said stop with respect to the cage. 10
9. In a filling head, a valve cage relatively movable with respect to the receptacle to be filled and inclosing a liquid-admission and an air-exit passage, a valve having therein 15 a port communicating with said air-exit passage, a gasket carried by the cage and movable thereon upon engagement with the receptacle for effecting a seal between the cage and receptacle, a member adjustable 20 with respect to said cage for limiting the movement of the gasket, a separate cover for inclosing the head and rotatably carried thereby, and means whereby said adjustable member is adjusted by rotation of said cover. 25
10. In a filling head, a valve cage, a valve for closing the same, a two part gasket comprising a resilient ring carried by the valve cage and tightly fitting the same, and a receptacle engaging ring loosely embracing 30 the valve cage, one of the opposing faces of said rings being substantially flat, and the other having a plurality of ribs. 35
11. In a filling head, a valve cage, a valve for closing the same, a two part resilient gasket carried by the cage and having associated therewith an air venting passage, and comprising a lower ring loose on the cage and an upper ring having a sealing fit on the cage, and a stop member against which 40 said gasket is forced by engagement with the receptacle to be filled thereby to cause said air venting passage to be closed. 45
12. In a filling head, a valve cage relatively movable with respect to the receptacle to be filled and inclosing a liquid-admission and an air-exit passage, a valve having therein a port communicating with said air-exit passage, a gasket carried by the cage and movable thereon upon engagement with
- the receptacle for effecting a seal between 50 the cage and the receptacle, a stop member in threaded relation with said cage for limiting the movement of the gasket, a separate cover for inclosing the head and rotatably carried thereby, a plurality of key-ways 55 formed on said cover, and a plurality of ribs on said stop member for engagement by said key-ways, whereby rotation of the cover adjusts the position of said stop member. 60
13. In a filling head, a valve cage relatively movable with respect to the receptacle to be filled and inclosing a liquid-admission and an air-exit passage, a valve having therein a port communicating with said air exit passage, a gasket carried by the cage 65 and movable thereon upon engagement with the receptacle for effecting a seal between the cage and the receptacle, a stop member carried by the cage and movable relatively thereto, means for moving said stop member, and means for preventing operation of 70 said moving means while the parts are in filling position. 75
14. In a filling head, a valve cage relatively movable with respect to the receptacle to be filled and inclosing a liquid admission and an air exit passage, a valve having therein a port communicating with said air exit passage, a gasket carried by the cage and movable thereon upon engagement with 80 the receptacle for effecting a seal between the cage and the receptacle, a stop member in threaded relation with said cage for limiting the movement of the gasket, a separate cover for inclosing the head and rotatably 85 carried thereby, means whereby rotation of the cover moves the stop member on the cage, and means for preventing rotation of the cover while the parts are in filling position. 90

In testimony whereof I have hereunto set my hand in the presence of two subscribing witnesses.
